UNITED STATES PATENT OFFICE.

PAUL A. SCHIMMING, OF HOPE, KANSAS.

WATER-CIRCULATING DEVICE FOR RADIATORS.

Application filed July 14, 1922. Serial No. 574,908.

To all whom it may concern:

Be it known that I, PAUL A. SCHIMMING, a citizen of the United States of America, residing at Hope, in the county of Dickinson and State of Kansas, have invented new and useful Improvements in Water-Circulating Devices for Radiators, of which the following is a specification.

The object of the invention is to provide means for producing a more effective circulation of the water between the water jacket and radiator of motor-driven vehicles and to this end means is provided for increasing the head of hot water and correspondingly increasing the head of cold water in the jacket to increase the rapidity of circulation between it and the radiator above what is ordinarily the case, thus maintaining the water in the circulatory system as a whole at a lower temperature for the more effective operation of the engine.

With this object in view the invention consists in a construction and combination of parts of which a preferred embodiment is shown in the accompanying drawings, wherein:

Figure 1 is a sectional view of a portion of a motor vehicle including the radiator and the upper water connection between the same and the motor jacket, to which is applied a device embodying the invention, the form of the illustrated device being especially adapted for Fordson tractors.

Figure 2 is a similar view of the device applied to the radiator of a car of the Ford type.

Figure 3 is a detail perspective view of the return pipe extension constituting the essential element of the invention.

The device consists essentially of a return pipe extension 10 having suitable means adapted to the particular radiator structure in connection with which it may be used for holding the same in place as a continuation of the upper or return water conductor 11 to the radiator 12 and which in the type of radiator shown in Figure 1 is provided with an upper water compartment 13. In this construction the extension 10 is provided with a flange 14 adapted to be engaged between the upper or cap section 13^a and the lower or body section 13^b of the radiator casing, and said extension is of such

a length as to carry it to a plane very close to but slightly below that of the surface of the water in the radiator, so that while the inner or discharge end of the extension is sealed or is submerged in the liquid contents of the upper compartment of the radiator, it is so close to the surface of said water as not to be materially effected by the weight of the water and therefore the resistance offered to the circulation of the water from the motor jacket to the radiator is minimized or is rendered practically negligible to increase the rapidity of the circulation and maintain the water in the system at a lower temperature than is possible under the present conditions.

In the form of the device which is shown in Fig. 2, as adapted for use in connection with a pleasure car, the return water pipe or connection 15 is engaged with a thimble 16 forming a part of the radiator 17, and the attachment 17' consists of a short length of tubing adapted to be inserted into said thimble to project upwardly into the upper water compartment 18 of the radiator to a point but slightly below the plane of the surface of the water in said compartment, as shown, for the purposes hereinbefore indicated. The extension is held in place by expanding the same in the thimble or by any equivalent agency.

Having described the invention, what is claimed as new and useful is:

The combination with the radiator and water jacket of a motor vehicle engine, the former being provided with an upper rearwardly extending water compartment and the latter being provided with a return pipe whose upper end is overhung by said water compartment, of a return pipe extension protruding through the lower wall of the upper water compartment and terminally connected with the return pipe of the radiator, the said extension terminating adjacent to the normal plane of the surface of the water in the upper compartment, and means for securing said extension respectively to the wall of said water compartment and to the extremity of the return pipe.

In testimony whereof he affixes his signature.

PAUL A. SCHIMMING.
